OSCAR BROCKMAN, OF LOUISVILLE, KENTUCKY.

SNAP-HOOK.

1,153,022.

Specification of Letters Patent. Patented Sept. 7, 1915.

Application filed March 9, 1915. Serial No. 13,226.

To all whom it may concern:

Be it known that I, OSCAR BROCKMAN, a citizen of the United States, residing at Louisville, in the county of Jefferson and State of Kentucky, have invented certain new and useful Improvements in Snap-Hooks; and I do hereby declare the following to be a full, clear, and exact description of the invention, such as will enable others skilled in the art to which it appertains to make and use the same.

This invention relates to buckles intended especially for use on harness and the like, and more particularly to those which combine a snap hook with the buckle; and the object of the same is to produce a device of this kind whose buckle end or body is adapted to receive a rope or other round harness element and whose hook end is adapted to be engaged with a ring or other similar member, the bend of the rope normally closing the throat of the hook to prevent the disengagement of said member but adapted to be drawn away from the buckle and deflected so as to permit such disengagement. The device therefore in effect becomes a snap hook and will be so described and claimed below, the round element being referred to as a rope and the member engaging the hook as a ring which might be that at the end of a bit if this device be employed on a bridle or the like. However, I do not wish to be limited in this respect, and therefore the following specification sets forth the preferred embodiment and use of the invention.

In the drawings: Figure 1 is a perspective view of the entire device in use. Fig. 2 is a section on line 2—2 of Fig. 1. Fig. 3 is a perspective view of a modification, viewed from the underside. Fig. 4 is a bottom plan view of an amplified form of the device in which the buckle end is adapted for receiving two ropes.

In the drawings the numeral 1 has been employed to designate a member which is to be engaged with the hook, and this member may be the ring usually employed at either extremity of a bit. If we assume that this invention is used in connection with a bridle composed mainly of rope, the numeral 2 may designate one stretch of said rope such as the cheek line, the numeral 3 the other stretch such as that leading rearward to the reins, and the numeral 4 the bend between these stretches and by which they are integrally united at their lower ends. No

novelty is claimed in the present application for the parts thus far described.

Coming now to the details of the present invention, the metallic member which is employed to connect the rope element with the ring or other member 1 is made all in one piece, and broadly speaking, includes a buckle with which the rope element is connected and a hook which engages the member 1. Preferably I make it of such metal or give it such finish that it is weather-proof and possesses suitable features of ornamentation. Its body 5 is by preference flat and when in use will stand substantially in a horizontal plane, its contour being oblong and preferably oval. Near its ends the body is pierced with round eyes 6 and 7, between which is a cross bar 8, and therefore the body may be said to be of frame shape with a transverse cross bar. The shank 9 of the hook projects integrally from one side of this frame at a point 10 in line with one end of said cross bar, and extends thence downward on a line about 45° from the plane of the body. At the lower end the shank bends gently and merges at 11 into the bill 12 of the hook which underlies the shank and is spaced therefrom a sufficient distance to permit the entry of the ring 1. The shank and bill preferably diverge in a direction away from the bend which connects them, and the tip 13 of the bill underlies the cross bar 8 and stands some distance below it where its end joins the frame; or in other words the tip of the bill stands in a plane through the adjacent sides of both eyes as indicated by the dotted line V. The extreme end of the tip may come to an angle as seen at 14, and its outer side is rounded as seen at 15. Otherwise all angles of this device are slightly rounded off so there will be no excessive wear on the elements or members with which it is engaged.

In use, the rope element is given a bend as at 4, one stretch 2 is passed up through the eye 6 and the other stretch 3 up through the eye 7, and when both stretches are drawn upward the bend closely underlies cross bar 8. In this position it extends across the tip 13 of the hook, and preferably rests gently across its rounded outer side 15 although in any event it will not touch the angle 14. The ring or other member 1 which may now be engaged in the hook cannot escape. To remove the ring, the operator grasps the bend of the rope and draws it

downward so that both stretches 2 and 3 move downward through the eyes 6 and 7; and then he moves the lower or bent portion of the rope element outward away from the hook as seen in dotted lines in Fig. 2, which naturally exposes a space out of which the ring 1 can pass. The latter is engaged with the hook by a reversal of this process. The adjustment of the rope element with what might be called the buckle end of this device is effected in much the same manner, whether the member 1 be engaged with the hook at that time or not. That is to say, the bend 4 of the rope is drawn downward 15 so that its stretches slip down through the eyes, and then instead of drawing both stretches upward to restore them to their former positions, the operator draws upward only that stretch 2 or 3 which it is 20 desired to lengthen—thereby of course shortening the other stretch correspondingly and causing the bend 4 to occur at a different point in the rope. But always 25 when the parts are restored to their working position, the side of the bend will lie very near to if not in actual contact with the tip of the hook, and therefore it constitutes the equivalent of the spring tongue used in popular types of snap hooks. If it 30 should so happen that the rope element is new or exceedingly stiff and the ring member quite large so that difficulty is experienced in passing the latter by the deflected parts of the rope and over the tip of the 35 hook, the ring might be twisted slightly and the fact that the outer side of the tip is rounded at 15 will assist its passage.

The element herein shown as rope, might, in fact, be a strap or other flexible element 40 as shown in Fig. 3. In that case the eyes 16 and 17 might yet be round but I would prefer to flatten them slightly and perhaps give them the oval shape shown, their longest diameters being parallel with each other 45 and at right angles to the length of the body frame. As the ordinary strap is comparatively thin, when this device is used with a strap it might be necessary to carry the tip of the hook up a little farther as seen in this 50 view, and therefore the throat of the hook would be narrower and the device would have to be used with a member which could pass through this throat. The operation would be the same as above described, and 55 when the device was in use the tip of the hook would stand almost if not absolutely in contact with the edge of the bend of the strap, the same as it is elsewhere illustrated as standing against the side, or I might say 60 the edge of the bend of the rope. In either case, however, I would have the eyes so close together that the flexible element must bend rather sharply between its two stretches and where it passes under the cross bar, for 65 the obvious purpose of giving this part of

the device a cling to said element and causing it to serve in the nature of a friction buckle. If one stretch were the cheek line and the other led to the reins as above suggested, it might often be desirable to adjust the cheek line so as to fit the bridle to horses of different sizes; and yet it would be quite undesirable that tension applied to one of the reins might accidentally draw the other through the buckle. Therefore 70 it may be said that the flexible element is held in its adjusted position on the buckle end of this device both by the constant tension on the stretch 2 and the sharp curvature of the bend 4 which closely underlies 75 the cross bar 8.

In Fig. 4 is shown an amplified form of this device wherein the hook 12 and the body 5 and cross bar 8 of the buckle are the same, but the frame is made a little wider and its 80 eyes a little larger so that it is adapted for receiving two ropes in case the bridle or other member which is to be connected with the buckle end of the device shall have two 85 ropes. The eye at one side of the cross bar 90 is elongated into two eyes 6' and 6'' which need not necessarily be entirely separated from each other, and the eye at the other side of the cross bar is similarly elongated into two eyes 7' and 7''. If the eyes of each 95 pair are not entirely separate, the sides of the frame will be formed with slight projections 5' extending inward, and the cross bar 8 at its mid-length will have slight projections 8' extending outward, the points 100 of these projections being by preference slightly spaced as shown so that each double eye is in effect practically divided into two 105 separate eyes. This view does not illustrate the use of the device when so constructed, but one rope will pass through the eye 6', will make its bend as shown at 4 in Fig. 1, and will then pass in the other direction through the opposite eye 7'; and the other 110 rope will similarly pass through one eye 6'', will make its bend, and will then pass through the other eye 7''. Between the two 115 stretches of each rope and where it is bent, it will underlie the cross bar 8; and the adjustment of either rope may be effected in 120 the manner described. The only difference would be that the rope whose stretches engage the eyes 6' and 7' will serve to close the 125 throat of the hook 12, and to open said throat its bend will have to be loosened up and laid over the bend of the other rope which occupies the eyes 6'' and 7''. In other words, it is the rope nearest the hook which serves as the snap for the same, and the rope remote from the hook can be adjusted without opening the throat of the hook at all. Manifestly this is but an amplification of the general idea above described.

What I claim is:

1. A hook comprising a body in the shape 130

of a frame with a bar across it producing two eyes, a hook-shank projecting rigidly from the frame adjacent one end of said bar, and a bill leading from the outer end of 5 said shank toward the body and terminating opposite and slightly remote from one end of said bar.

2. A hook comprising a substantially flat body in the shape of a frame with a bar 10 across it producing two eyes, a hook-shank projecting rigidly from the frame and on a line at an angle of about 45° to the plane of said frame, and a bill leading backward from and standing beneath said shank and 15 terminating opposite and slightly remote from said bar.

3. A hook comprising a substantially flat body having through it two round eyes, a hook-shank projecting rigidly from one side 20 of the body and on a line at an angle to its plane, and a bill leading backward from the shank to a point near said body and on a plane passing through one side of both eyes.

4. A combined buckle and hook comprising a frame-like body with a bar across its center producing two eyes, and a hook whose shank projects obliquely from said body opposite said bar and whose bill underlies the 25

shank and has its tip rounded off, for the purpose set forth.

5. A combined buckle and hook comprising a flat body having a pair of eyes and a cross bar between them, and a hook whose shank projects rigidly from one side of the body and whose bill underlies said bar and 35 is spaced therefrom, the tip of the bill standing in a plane through such tip and the nearest side of both eyes, for the purpose set forth.

6. A combined buckle and hook comprising a substantially flat body having through it a pair of double eyes separated by a cross bar and surrounded by a frame, the sides of said bar and frame having projections extending toward each other so as to separate the eyes of each pair, and a hook whose shank projects rigidly from one side of the frame opposite the end of the cross bar and the tip of whose bill stands in a plane below the frame at one end of the cross bar. 40 45 50

In testimony whereof I affix my signature in presence of two witnesses.
